LAPPING TOOL

Joseph B. Kowalski, Detroit, Mich., assignor,
by mesne assignments, to Micromatic Hone
Corporation, Detroit, Mich., a corporation of
Michigan

Application May 9, 1927. Serial No. 189,933

16 Claims. (Cl. 51—184.3)

This invention relates to lapping tools and more particularly to improvements in devices of this character tending to simplify and render the same more efficient.

5 The invention has as one of its objects to provide a lapping or grinding tool comprising a plurality of lapping members mounted for radial adjustment upon a body and to provide means whereby each lapping member may be rocked 10 longitudinally for the purpose of accommodating the tool to tapered surfaces.

The several objects, advantages and the novel details of construction of this invention will be made more apparent as this description proceeds, 15 especially when considered in connection with the accompanying drawings wherein:

Figure 1 is an elevational view of a lapping tool constructed in accordance with this invention;

Figure 2 is a vertical longitudinal sectional 20 view through the device;

Figure 3 is a bottom end elevation;

Figure 4 is a transverse sectional view taken substantially on the plane indicated by line 4—4 in Figure 2; and

25 Figure 5 is a similar sectional view taken substantially on the plane indicated by lines 5—5 in Figure 2.

Referring now particularly to the drawings wherein like reference characters indicate like parts, it will be noted that the tool comprises a body 10, provided with a central longitudinal bore 11, radially arranged recesses 12 opening into the outer surface of the body and radial slots 13 communicating respectively with the bore 11 and the recesses 12. The body is provided with cap-plates 14 at the ends thereof, preferably formed separately from the body and secured thereto as, for instance, by means of bolts 15. These cap-plates 14 define the ends of 30 the recesses 12 which as illustrated, extend longitudinally of the body.

Arranged in each recess 12 is a lapping member indicated generally by the reference character 16 and comprising a shoe or hone guiding member 17 carrying a hone or grinding stone 18. The stones 18 are secured in recesses in the outer faces of the shoes and may be secured against endwise displacement by means of pins 19. The ends of the shoes 17 are extended beyond the ends of 35 the stones and are engaged by a circular resilient member, as for instance, a coil spring 20, whereby the several lapping members are all resiliently urged radially inwardly. The end surfaces of the shoes 17 are rounded or curved as indicated at 40 21 on an arc, the center of which is arranged sub-

stantially or approximately mid-way of the length of the shoe. These arcuate or curved surfaces at the ends of each shoe are adapted to engage the cap-plates 14 and to permit of a longitudinal rocking of the shoes in a manner, and for a purpose, to appear more fully hereinafter.

Arranged longitudinally of the bore 11 is a shaft or rod 22 provided with two sets of opposite screw threads 23. Adjustable blocks 24 engage the threaded portions of the shaft 22 and upon rotation of this shaft are adapted for adjustment longitudinally of the body within the adjacent portions 25 of the bore 11. The outer surface of each of the blocks 24 is fluted or provided with a plurality of circumferentially spaced longitudinally extending grooves 26.

Arranged in the radial slots 13 are plate members 27 each of which is provided with a pair of inclined or bevelled surfaces 28 which surfaces engage in the recesses or grooves 26 of the blocks 24. The plates 27 are therefore supported by the pair of blocks 24 and any longitudinal adjustment of these blocks by reason of rotation of shaft 22, causes a corresponding radial adjustment of plates 27. The outer edge 29 of each plate 27 projects into or above the bottom of one of the recesses 12 so that each plate 27 acts as a support for one of the shoes 17 of the lapping members.

As a consequence of this construction it will be apparent that each lapping member is left unsupported at its ends even though any radial rectilinear movement is prevented. Thus the lapping members may be rocked upon the plates 27 to, for instance, the dotted line position shown in Figure 2. This rocking movement is furthermore permitted by reason of the rounded ends 21 of the shoes 17.

Longitudinal movement of shaft 22 is prevented by means of a set screw 30 threaded into the body and engaging in an annular groove 31 formed in the shaft 22 at one end thereof. The shaft may be rotated, for the purpose of adjusting the lapping members, by means of an adjusting rod 32 pivotally connected to the end of shaft 22 as indicated at 33. While the tool may be rotated within the cylinder in any suitable manner, I have shown an operating shaft 34 universally connected thereto as indicated at 35.

The operation of the tool will be obvious from the foregoing and need not be recited herein in detail. It will be noted however, that the lapping members may be adjusted radially by rotating shaft 22 which will move the blocks 24 toward or away from one another. The action of these

100

105

110

blocks upon the inclined surfaces 28 of the plate members 27 cause these members to move radially outwardly and to consequently move the lapping members radially outwardly against the action of springs 20. While the outer edges 29 of the plate members 27, which are parallel with the longitudinal axis of the tool, rigidly support the lapping members in the ordinary use of the tool, nevertheless each lapping member may be rocked longitudinally because the plates 27 provide support intermediate the ends only of the shoes 17. By reason of the engagement of the plates 27 in the slots 26 of the blocks 24, any rotation of these blocks, upon adjustment of the shaft 22, is prevented.

While an embodiment of the invention has been illustrated and described herein somewhat in detail, it will be readily apparent to those skilled in the art that various changes may be made in many of the essential and all of the non-essential details without departing from the spirit and scope of the invention and to this end reservation is made to make such changes as may come within the purview of the accompanying claims.

25 What I claim as my invention is:

1. In a lapping tool, a body provided with radial recesses in the outer surface thereof, lapping members arranged in said recesses and means for adjustably and rockably supporting said lapping members including radially adjustable plate members projecting into said recesses and engaging said lapping members.

30 2. In a lapping tool, a body provided with radial recesses in the outer surface thereof, lapping members arranged in said recesses and means for rockably supporting and radially adjusting said lapping members including radially adjustable plate members projecting into the bottom of said recesses and engaging the lapping members intermediate their ends.

35 3. In a lapping tool, a body provided with a central longitudinal bore and radial recesses in the outer surface thereof, hone guiding members arranged in said recesses, radially adjustable plate members projecting into the bottom of said recesses for supporting said guiding members, and adjustable blocks in said bore engaging inclined surfaces on said plate members for radially adjusting the same.

40 4. In a lapping tool, a body provided with a central longitudinal bore, radial recesses in the outer face thereof and radial slots connecting said bore to said recesses, a threaded shaft in said bore, adjustable blocks on said shaft, plate members arranged in said slots and provided with inclined surfaces engaging said blocks, said plate members extending into said recesses and hone guiding members in said recesses supported by said plate members.

45 5. In a lapping tool, a body provided with a longitudinal bore and radial slots communicating therewith, adjustable blocks within said bore, radially adjustable plates arranged in said slots provided with inclined surfaces engaging said blocks and hone guiding members slidably secured to said body in engagement with said plates.

60 6. In a lapping tool, a body provided with a central longitudinal bore, hone guiding members arranged in recesses in the outer face of said body, radial slots extending from said bore to said recesses, adjustable blocks arranged in said bore and plate members arranged in said slots

engaging said blocks and projecting into said recesses for supporting said guiding members.

65 7. In a lapping tool, a body formed with a longitudinal bore and radial slots, radially adjustable hone guiding members carried by said body, adjustable blocks in said bore and plate members in said slots engaging said guiding members intermediate the ends of said members, said plate members being radially adjustable upon movement of said blocks.

80 8. In a lapping tool, a body formed with a central longitudinal bore, recesses in the outer surface and radial slots communicating with said recesses and bore, adjustable blocks in said bore, plate members in said slots engaging said blocks and hone guiding members arranged in said recesses and engaging said plates intermediate the ends of said guiding members whereby a radial and rockable adjustment of said guiding members is permitted.

85 9. In a lapping tool, a body provided with radial recesses in the outer surface thereof, end plates secured to said body, lapping members arranged in said recesses and provided with curved end portions engaging said end plates, and radially adjustable plate members projecting into the bottom of said recesses and engaging the lapping members intermediate their ends for permitting said lapping members to be radially and rockably supported in said recesses.

90 10. In a lapping tool, a body provided with radial recesses in the outer surface thereof, end plates secured to said body, lapping members arranged in said recesses and provided with curved end portions engaging said end plates, and means located in said recesses and supporting said lapping members intermediate their ends for permitting a rocking movement of said members in said body.

95 11. In a lapping tool, a body provided with radial recesses in the outer surface thereof, end plates secured to said body, lapping members arranged in said recesses and provided with curved end portions engaging said end plates, plate members positioned in said recesses and supporting said lapping members intermediate their ends, and resilient rings at opposite ends of said lapping members normally retaining said members in parallel relation to said plate members but permitting a rocking movement thereof with respect to said plate members.

100 12. In a lapping tool, a body formed with radial recesses and a bore, a pair of blocks in said bore, means for adjusting said blocks, hone guiding members in said recesses, and means for permitting a longitudinally rockable movement of said guiding members in said recesses including plate members supporting said guiding members and slidably radially in said body by means of said blocks.

105 13. In a lapping tool, a body provided with radial slots, radially adjustable plate members non-rockably arranged in said slots, and hone guiding members rockably supported within said radial slots upon said plate members.

110 14. In a grinding device, a head having a longitudinal bore, a series of abrading members carried by the head radially adjustable relative thereto, a control element in the said bore arranged for adjustment of the abrading members and a single element interposed between each abrading member and the control element, unattached to either thereof, and through the medium of which an adjustment of the control ele-

ment varies the position of the abrading members relative to the axis of the tool.

15. In a grinding device, a head having a longitudinal bore, a series of abrading members carried by the head and radially adjustable relative thereto, a control element in the said bore for adjusting the abrading members, said control element being movable longitudinally of the body in either direction, and a single element interposed between each abrading member and the control element unattached to either thereof and together with the control element positively limiting the extent of contraction of the abrading members.

15 16. In a lapping tool, a shank, a tubular frame

positioned upon said shank having a series of spaced apertures therein at substantially the longitudinal center thereof, a cam member also positioned within the tubular frame, blocks slidably mounted within said apertures and engageable with said cam member, a plurality of stone holders pivotally mounted upon said frame at substantially the longitudinal center thereof and having portions extending through the apertures aforesaid rockably engaging said blocks, and means for positively moving said cam longitudinally of the tubular frame for adjusting the stone holders radially.
